No. 838,258.

PATENTED DEC. 11, 1906.

E. LAMOUREUX.

SHUTTLE.

APPLICATION FILED JULY 13, 1905.

UNITED STATES PATENT OFFICE.

EDMOND LAMOUREUX, OF MONTREAL, QUEBEC, CANADA, ASSIGNOR OF
ONE-HALF TO JOSEPH ARTHUR TOUSIGNANT, OF MONTREAL, CANADA.

SHUTTLE.

No. 838,258.

Specification of Letters Patent.

Patented Dec. 11, 1906.

Application filed July 13, 1905. Serial No. 269,466.

To all whom it may concern:

Be it known that I, EDMOND LAMOUREUX, a citizen of the United States of America, residing in the city and district of Montreal, in the Province of Quebec, Canada, have invented certain new and useful Improvements in Shuttles; and I do hereby declare that the following is a full, clear, and exact description of the invention, such as will enable others skilled in the art to which it appertains to make and use the same.

The object of this invention is to provide a device whereby shuttles may be quickly and easily threaded, a further object being to provide a device of this class which obviates the necessity for the long curved slot heretofore employed in the walls of shuttles and which tend to weaken the same, and a still further object being to provide such a device which is detachably connected with a shuttle, which is simple and positive in operation, and comparatively inexpensive.

My invention is fully described in the following specification, of which the accompanying drawings form a part, in which suitable reference characters are used to indicate the separate parts in each of the views, and in which—

Figure 1 is a plan view of a shuttle provided with my invention; Fig. 2, a side elevation thereof; Fig. 3, an enlarged fragmentary plan view of the threading device shown in position with the shuttle shown partly in transverse section; Fig. 4, a view similar to Fig. 3 with a part of my invention broken away; Fig. 5, a section on the line 5 5 of Fig. 4, and Fig. 6 a perspective view of my threading device detached from the shuttle.

In the drawings forming part of this specification I have shown a shuttle 4 and within which is mounted a bobbin 5 of the usual or any desired construction, and in the practice of my invention I provide a substantially circular aperture 6 in the wall of the shuttle.

At 7 I have shown a tube formed of a plate rolled to form the same and one of the ends of which extends a predetermined distance beyond the tube 7 to form a guide-lip 8, the outer edge of which is inclined, as shown at 9, and the tube 7 projects into the aperture 6 and substantially through the wall of the shuttle, which is preferably channeled externally in the position of the aperture 6.

The wall of the tube 7 is provided with a

longitudinally - arranged opening 11, into which the shorter end of the plate forming said tube extends, said end being formed into a tongue 12 of less diameter than the opening 11, as clearly shown in Fig. 4.

At 13 I have shown a plate which is formed on or integral with the guide-lip 8, the object thereof being to provide means whereby the tube 7 may be secured in the transverse recess 14 of the shuttle, and the plate 13 is secured to said shuttle by means of a screw 15; but, if desired, various other means of securing the tube 7 may be employed, such as the pins 16 or other mechanical equivalents.

When it is desired to pass the thread from the bobbin 5 through the wall 10 of the shuttle, the end thereof is drawn out, and said thread is then passed beneath the guide-lip 8, this operation forming a loop which slides down the inclined edge 9 when the end of the thread is pulled backwardly, and this loop of the thread is thereby guided entirely through the wall 10 and into a position where the same may be grasped and drawn outwardly, thereby withdrawing the end of said thread, and the threading of the shuttle is accomplished.

In the operation just described the thread passes over the tongue 12 in its passage to the interior of the sheet-metal tube 7 and also bears against the ends of the opening 11, and a tension (on the thread) is thus produced.

It will be observed that a small circular opening in the wall 10 is all that is necessary, and the said wall is not weakened thereby, and the frequent breakage common to shuttles as previously constructed is prevented, this feature constituting the important feature of my invention, and it will be understood that various changes in and modifications of the construction herein shown and described may be made without departing from the spirit of my invention or sacrificing its advantages.

Having fully described my invention, what I claim as new, and desire to secure by Letters Patent, is—

1. In a shuttle, the combination of a shuttle-body provided with a bobbin-cavity and an aperture in one wall extending to said cavity, the said wall being otherwise unbroken, and means in said cavity for guiding

- a bobbin-thread through said aperture, substantially as described.
2. In a shuttle, the combination of a shuttle-body provided with a bobbin-cavity and an aperture in one wall extending to said cavity, the said wall being otherwise unbroken, and an inclined guide in said cavity for guiding a bobbin-thread through said aperture, substantially as described.
- 10 3. In a shuttle, the combination of a shuttle-body provided with a bobbin-cavity and an aperture in one wall extending to said cavity, the said wall being otherwise unbroken, a tube extending within said aperture, and an inclined guide in said bobbin-cavity for guiding a bobbin-thread through said tube, substantially as described.
- 20 4. In a shuttle, the combination of a shuttle-body provided with a bobbin-cavity and an aperture in one wall extending to said cavity, the said wall being otherwise unbroken, a tube extending within said aperture, and an inclined guide carried by said tube for guiding a bobbin-thread there-through, substantially as described.
- 25 5. In a shuttle, the combination of a shuttle-body provided with a bobbin-cavity and an aperture in one wall extending to said cavity, the said wall being otherwise unbroken, a tube extending within said aperture and provided with an open side, and means within said cavity for guiding a bobbin-thread through such open side of said tube, substantially as described.
- 35 6. In a shuttle, the combination of a shuttle-body provided with a bobbin-cavity and an aperture in one wall extending to said cavity, the said wall being otherwise unbroken, a tube extending within said aperture, a tongue carried by said tube, and means within the bobbin-cavity for guiding a bobbin-thread against said tongue and through said tube, substantially as described.
- 45 7. In a shuttle, the combination of a shuttle-body provided with a bobbin-cavity and an aperture in one wall extending to said cavity, the said wall being otherwise unbroken, a tube extending within said aperture and provided with a peripheral opening, a tongue projecting into said opening, and means within the bobbin-cavity for guiding a bobbin-thread against said tongue and through said tube, substantially as described.
- 50 8. In a shuttle, the combination of a shuttle-body provided with a bobbin-cavity and an aperture in one wall extending to said cavity, the said wall being otherwise unbroken, a tube extending within said aperture and provided with an open side, and means in the bobbin-cavity for guiding a bobbin-thread through such open side of said tube, substantially as described.
- 55 9. In a shuttle, the combination of a shuttle-body provided with a bobbin-cavity and an aperture in one wall extending to said cavity, the said wall being otherwise unbroken, guiding means in said cavity for guiding a bobbin-thread through said aperture, and a plate carried by said guiding means for attachment to the shuttle-body, substantially as described.

In witness whereof I have hereunto set my hand in the presence of two witnesses.

EDMOND LAMOUREUX.

Witnesses:

ARTHUR TOUSIGNANT,
T. MYNARD.
